BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE AND METHOD FOR USE IN SHAPING UPPERS.

Application filed April 22, 1922. Serial No. 556,063.

This invention relates to the shaping of upper materials in the manufacture of boots and shoes. It is one important object of the invention to provide a method and machine for use in the manufacture of a type of shoe in which the upper is secured in lasted relation to the insole by adhesion, and the invention is accordingly illustrated herein in its application to the manufacture 5 of such shoes, for example tennis shoes or sneakers, and more particularly as applied to the pulling over and lasting of the forepart of the shoe. It will be recognized, however, that in many of its important novel 10 aspects the invention is not restricted in utility to the manufacture of shoes of this particular type, nor limited to combined pulling-over and lasting machines or methods nor to operations performed upon the 15 forepart of the shoe.

Among its important features, the invention provides a novel organization of means for wiping an upper heightwise of the last (i. e., "upwiping" the upper) and for laying 20 its margin inwardly over the bottom of the last, the machine herein shown having automatic means for upwiping the upper as the overlaying means moves toward the shoe. In the application of the invention 25 to toe end lasting, the machine illustrated comprises in its organization a toe wiper support which is moved toward the toe and carries wipers for laying the margin of the upper about the toe inwardly over the sole 30 or insole (hereinafter frequently termed for convenience the "sole"), and a toe embracing wiping device or band which embraces the upper about the toe and is operated by the movement of the wiper support to wipe the 35 upper heightwise of the toe. It is a further advantageous characteristic of the construction herein shown that the wiping of the upper heightwise of the last is completed prior to any substantial movement of the 40 overlaying means inwardly over the bottom of the last, after which the upwiping means holds the upper against the lateral periphery of the last during the overlaying operation.

50 A further feature of the invention consists in a novel organization of means for pulling

an upper over a last, for wiping the upper heightwise of the last and for laying the margin of the upper inwardly over the bottom of the last. In its embodiment of this 55 feature, the machine herein shown comprises means for performing upwiping and overlaying operations on the upper in time relation to each other after the upper has been pulled, and means for releasing the upper 60 from the upper pulling means in time relation to the upwiping operation. For the purposes of toe end lasting, the machine illustrated has automatic means for embracing and clamping the upper about the toe 65 and for then releasing the toe gripper from the upper, after which the upwiping and overlaying operations are performed in time relation. It is one of the objects of the invention to operate upon the shoe without 70 any substantial overdrawing movement of the toe gripper, such as has been effected heretofore in machines of the illustrated type by movement of the wiper carrying front arm toward the toe, in order to avoid 75 danger of forming folds in the margin of the upper of undesirable prominence at the corners or sides of the toe, and a further feature of the invention is to be recognized in means for accomplishing this object, the 80 construction shown comprising means for releasing the toe gripper from the upper prior to any substantial movement of the front arm to carry the wipers toward the toe.

In the lasting of shoes of the type which 85 includes a comparatively flexible insole of rubber composition and in which the margin of the upper is secured to the insole in the lasting operation by adhesion, it is necessary to guard against wrinkling or displacement of the insole by the lasting pressure and also against adhesion of the margin of the upper to the insole prematurely or before the upper has been conformed tightly and smoothly to the last and the insole along 90 the edge of the shoe bottom. For the purpose, among others, of dealing satisfactorily with such conditions, the invention in a further important aspect provides a novel 95 method and a novel machine organization whereby lasting operations on the shoe are 100 performed by the aid of a flexible apron in

engagement with the upper materials. As applied for example to toe end lasting, and in accordance with the illustrative practice of the method, a flexible apron embracing the upper about the toe is utilized both for wiping the upper heightwise of the toe and for gathering and laying the margin of the upper inwardly over the sole or insole. By reason of its flexibility the apron conforms closely to the contour of the last, and by its use the margin of the upper is bent inwardly and pressed into adhering relation to the sole while the upper is held tightly and smoothly conformed to the contour of the sole along the edge of the last bottom and without danger of displacing the sole or of pressing the margin of the upper into adhering relation to the latter prematurely such as has been encountered heretofore in the use of wipers directly engaging the upper. For better insurance of adequate upwiping pressure, and to assist in holding the upper during the subsequent overlaying operation, the apron may be pressed inwardly against the upper, for example by clamping it about the toe as herein shown; and in further accordance with the practice herein illustrated the apron is pulled heightwise of the last in the upwiping operation and is held by its opposite ends while pressure is applied between its ends to lay the margin of the upper over the sole. Improved results, moreover, are secured by the use of an elastic apron, for example of rubber, which as herein illustrated is stretched to increase its frictional drag on the upper in the upwiping operation and is held in stretched condition as pressure is applied between its ends to lay the margin of the upper inwardly, thus further insuring that the upper will be tightly and smoothly conformed to the last and the sole along the edge of the last bottom.

The above and other features of the invention, including novel gripper releasing mechanism together with certain details of construction and combinations of parts, and also the novel method aspects of the invention, will now be more particularly set forth by reference to the accompanying drawings and pointed out in the claims.

In the drawings:

Fig. 1 is a view in side elevation of the head portion of a machine in which features of the invention are embodied;

Fig. 2 is a side elevation with parts omitted, illustrating more fully the means for pulling the upper at the end of the toe and for lasting the toe, and showing a shoe in the position in which it is presented to the machine by the operator;

Fig. 3 is a view similar to Fig. 2 showing the parts in the positions which they assume at the end of the toe lasting operation;

Figs. 4 and 5 are detail views of the parts

which operate upon the toe, showing the parts in successive positions which they assume between the positions illustrated in Figs. 1 and 2;

Fig. 6 shows substantially in front elevation one of the side grippers with the associated clamping and overlaying devices at that side of the shoe;

Fig. 7 is a plan view showing the flexible apron and its clamping device substantially in the position illustrated in Fig. 4;

Fig. 8 is a sector on the line 8—8 of Fig. 7;

Fig. 9 is a section substantially on the line 9—9 of Fig. 3;

Fig. 10 is a detail view of portions of the toe gripper tripping mechanism;

Fig. 11 is an inverted plan view of a portion of the sole rest, and

Fig. 12 is a detail view in side elevation of a portion of the sole rest controlling mechanism, the parts there shown being mounted on the opposite side of the machine from that illustrated in Fig. 1.

The invention is herein illustrated in its application to a well known type of pulling-over machine organization, the general features of which are shown and described in United States Letters Patent No. 1,029,387, granted on June 11, 1912 upon an application of R. F. McFeely, to which reference may be made for a better understanding of such details of construction as are not hereinafter particularly described. Machines of this type include in their general organization a toe gripper 2 and opposite side grippers 4 connected respectively to gripper levers 6 and 8 which are operated by cams on a cam shaft 10 to grip and pull the upper yieldingly through tensioning springs one of which is seen at 12 in Fig. 1. In the construction shown (Figs. 2 and 10) the toe gripper comprises jaws 14 which are curved

for engagement with the upper round the end of the toe, and the side grippers (Figs. 6 and 7) comprise jaws 16 for pulling the upper at the opposite sides of the forepart at the rear of the toe end. It will be understood that the shoe is positioned initially in engagement with a sole rest (Fig. 2), to be hereinafter more particularly described, with the margin of the upper within the open jaws of the toe and side grippers. In the usual operation of machines of this general type the cam shaft 10, upon the starting of the machine, makes a partial revolution to cause the grippers to close and to pull the upper and then comes to rest with the upper held under tension to permit any adjustment of the upper which may be necessary by manipulation of one or more of the grippers.

It is contemplated that the machine herein shown also may operate in this manner, although the features of the invention may be embodied in a machine having a continu-

ous cycle of operations. In the upper pulling stage of the cycle the sole rest receives a short downward tipping movement from a cam 18 on the shaft 10, and a heel rest 20 is moved forwardly into supporting engagement with the heel end of the shoe.

When the machine is again started, opposite side clamping and supporting devices 22 (Fig. 6) are moved inwardly into operative relation to the shoe by the action of side clamp arms 24 at the opposite sides of the shoe, and either immediately thereafter, or after a subsequent pause in the cycle of the machine as predetermined by the particular type of starting and stopping means which is utilized, the margin of the upper is laid inwardly over the sole about the toe and at the sides of the forepart and is fastened to the sole. The devices for overlaying and fastening the margin of the upper at the toe end and at the sides of the forepart are carried respectively by a front arm 26 and opposite side arms 28 which are swung inwardly toward the shoe by connections to a rearwardly movable slide 30 which serves also through well known means to cause the opposite side grippers 4 to draw the margin of the upper inwardly over the sole, the side grippers being tripped to release the upper by engagement of mechanism on the arms 28 with latches 32 (Fig. 6) on these grippers. In the machine herein shown the toe gripper also is tripped automatically to release the upper in a manner which will be more particularly described hereinafter. After the upper has been laid inwardly over the sole and has been pressed into adhering relation to the sole, as will also be hereinafter set forth in detail, the parts of the machine are returned to their starting positions and the shoe is released.

For purposes of the present invention the machine herein shown is provided with means for embracing the toe of the shoe and for wiping the upper heightwise of the toe toward the edge of the sole before its margin is laid inwardly over the bottom of the sole, such means comprising a flexible wiping device or apron 34 which in the construction shown consists of a sheet of elastic material, such as vulcanized rubber, of suitable thickness to render it durable for the purposes in view and of a width to extend continuously round the toe from one side of the toe to the other. The apron 34 is secured at its upper end to a curved holder or support 36 mounted on arms 38 which are pivoted at 40 on opposite sides of a supporting plate 42 fast on the front arm 26. At its lower end the apron 34 is connected to a further support or clamping device which serves to press the apron inwardly about the toe comprising a chain-like arrangement of links 44 jointed together and arranged to extend for a con-

siderable distance heightwise of the toe and to extend also continuously round the toe from one side of the toe to the other. For supporting and operating the chain 44 the front arm 26 has thereon a carrier comprising a casing 46 provided with trunnions 48 which are mounted in lugs 50 secured to the plate 42. Housed within the casing 46 by means of a cover plate 52 on the lower side of the casing is a slide 54 which at its front end has a cross-arm 56. On the opposite end portions of the cross-arm 56 are pivotally mounted supporting arms 58 to which the opposite ends of the chain 44 are connected. A tension spring 60 connected to rearward extensions of the arms 58 tends to swing the arms in directions for straightening the chain, the spring thus affording resistance to insure adequate pressure of the chain and the flexible apron against the end of the toe as they are wrapped about the toe. Midway between its opposite ends the chain 44 is further supported and controlled by a slide 62 to which the middle links of the chain are pivoted, this slide being mounted upon the top of the main slide 54, as shown in Fig. 8. Carried by the slide 62 is a pin 64 which projects within a slot 66 in the slide 54, this pin and slot arrangement permitting limited relative movement between the slides 54 and 62 in the direction of the length of the shoe and limiting forward movement of the slide 62 under the influence of the spring 60 when the parts are in their idle positions. In the construction shown the apron 34 is suitably fastened to the chain supporting members 58 and 62, as by screws 67. It will be evident that the apron serves as a facing for the chain 44, the chain and adjacent parts of the apron constituting what may be termed a toe band for embracing and clamping the upper about the toe and for wiping it heightwise of the toe.

For applying the chain 44 and the apron to the shoe there are provided springs 68 which for the greater portion of their length are housed within the slide 54 and bear at their outer ends upon adjusting screws 70 mounted in an upturned end portion of the cover plate 52. The slide 54 is arranged to be held in retracted position, as indicated in Fig. 2, by a latch 72 which is slidably mounted in a boss 74 on the casing 46 and is pressed downwardly by a spring 76 into position for engagement with an end of a plate 78 which is fast on the slide 54 in line with the slide 62. In this position of the parts the toe band parts are retracted from the shoe and the springs 68 are under comparatively high compression.

The machine herein shown is so constructed as to apply the flexible apron, or toe band, to the shoe substantially at the beginning of the second stage of the cycle as the side clamp arms 24 are swung toward

the shoe and while the toe and side grippers are holding the upper under tension. Such application of the band to the shoe is effected by the springs 68, when permitted by refractive movement of the latch 72, the springs then projecting the slide 54, together with the chain and the lower part of the apron 34, forwardly toward the toe of the shoe, pressure being applied first at the end of the toe and the apron then being wrapped about the toe by the movement of the slide 54 and the arms 58 relatively to the supplemental slide 62. Movement of the latch 72 to release or trip the slide 54 is effected in the construction shown by the action of a cam operated slide 80 (Fig. 1) which in machines of the type illustrated serves to swing the side clamp arms 24 inwardly toward the shoe. For operating the latch the slide 80 carries a lug 82 in which is formed a slot 84 to receive the end of a link 86 provided with a shoulder 88 to be engaged by the lug as the slide 80 moves toward the right (Fig. 1) to operate the clamp arms. The link 86 is connected to one arm of a bell-crank 90 the other arm of which is connected by a link 92 to an arm 94 fast on a rock shaft 96 on the rear portion of the frame of the machine, this rock shaft having fast thereon another arm 98 which is connected by a link 100 to a tripping member 102 pivotally mounted on a holder 104 on the frame. The member 102 has a forwardly projecting arm which is forked to embrace the upper end of a rod 106, the latter being pivoted at its lower end to the upwardly extending shank of the latch 72. Near its upper end the rod 106 has a shoulder 108 which is engaged by the member 102 to impart upward movement to the rod 106 to withdraw the latch from engagement with the plate 78 when the member 102 receives its operative movement from the cam slide 80. As will be evident by reference to Fig. 3, the tripping member 102 in its continued movement slips from engagement with the shoulder 108 and thus releases the rod 106, permitting the spring 76 to return the latch 72 into latching position as soon as permitted by relative movement of the parts at a later time in the cycle.

In the position which the toe band assumes in response to the action of the springs 68, as illustrated in Fig. 4, the band is wrapped completely about the toe, the springs 68 acting with sufficient force to hold the upper from relaxing when it is released by the toe gripper. In the machine herein shown there is provided means for tripping the toe gripper automatically to cause it to release the upper at a considerably earlier time in the cycle than has been the practice heretofore, and prior to any substantial movement of the front arm 26 toward the toe, thus avoiding any substantial rearward overdrawing movement of the toe gripper with the consequent tendency on shoes of the class herein shown to form in the margin of the upper pleats of undesirable prominence at the corners of the toe. For the purposes in view the toe gripper in the construction shown is tripped immediately after the toe band is applied in holding engagement with the upper, and by a part of the same means whereby the latch 72 is operated. The connections for effecting the tripping of the gripper comprise an arm 110 on the rock shaft 96, to which is connected one end of a rod 112, the other end of the rod being mounted slidably in a socket formed in a sleeve member 114 (Fig. 10) pivoted on an arm 116 which is fast on a forked member 118 rotatably mounted on a bracket 120 on the frame. The member 118 is connected by a universal joint to a rod 122 which telescopes within and is keyed to a member 124, the latter being connected by a universal joint to a tripping member 126 which is pivoted on the side of the toe gripper casing by means of a screw stud 128. The member 126 is provided with a finger 130 which is arranged to engage the usual latch member 132 whereby the toe gripper jaws are tripped to cause them to release the upper. A spring 134 tends to hold the member 118 and its connected parts, including the tripping member 126, in idle position, but permits the parts to be operated by the rod 112 to press the latch 132 inwardly. Between the rod 112 and the sleeve member 114 there is provision for sufficient lost motion to insure that the toe band will be applied firmly about the toe in upper holding position before the toe gripper releases the upper.

After the toe band has been applied about the toe and the toe gripper has released the upper, the next operation of the machine is to wipe the upper upwardly toward the edge of the sole to conform it smoothly and tightly to the contour of the last without objectionable wrinkles in any part which is visible in the finished shoe. The upwiping operation is effected by bodily upward movement of the toe band chain 44 and of the apron 34, accompanied by an upward stretching of the elastic apron to increase its frictional drag on the upper. These operations are accomplished by a swinging movement of the carrier 46 about the axis of the trunnions 48 and an accompanying movement of the arms 38 about the pivots 40, the movements of these parts being effected in response to the swinging movement of the front arm 26 toward the shoe. For swinging the carrier 46 there are pivoted on studs 136 at opposite sides of the plate 42 arms 138 which are provided with cam extensions 140 in engagement with the carrier 46. At their upper ends the arms 138 carry

- adjustable bearing screws 142 which are arranged to engage the front face of a bearing block 144 fast on the frame of the machine. A spring 146 which is connected at its opposite ends to said block and to the carrier 46 serves to hold the carrier against the cam members 140.
- Swinging movement of the arms 38 to lift the apron holder 36 is effected by cam plates 148 which are secured to the block 144 and have edge faces engaged by rolls 150 on the arms 38. To hold the rolls against the cam plates, springs 152 are connected to the arms 38. As the front arm 26 is swung toward the shoe the toe band chain 44 and the apron 34 are thus lifted bodily, with the apron in wiping engagement with the upper about the toe, the chain yielding as required to maintain the apron in close conformity to the shape of the toe. The support 36 for the upper end of the apron receives a greater upward movement than the chain and thus acts to stretch the elastic apron and thereby to increase the frictional drag of the apron on the upper as well as to assist in holding the upper tightly in conformity to the contour of the last. As this upwiping action is taking place the upper portion of the apron is carried forwardly by its support 36 to bring the apron in to effective engagement with the upper substantially at the edge of the sole, the parts assuming at the end of the upwiping operation substantially the positions illustrated in Fig. 5.
- 35 The gathering and overlaying of the margin of the upper about the toe is effected by the action on the apron 34 of toe embracing wipers 154 which are mounted on a carrier plate 156 (Fig. 9) for swinging movement laterally of the shoe about axes afforded by pivot studs 158, the wipers being hinged together and provided with wiping edges which extend continuously about the toe from one side of the toe to the other side.
- 40 Since the manner in which these wipers are mounted is substantially as illustrated in Letters Patent No. 1,541,820, granted upon my application on June 16, 1925, it need not be further described in detail. For overlaying the upper at the sides of the forepart at the rear of the toe end the machine is provided with wipers 160 (Figs. 6 and 9) which have upturned inner ends to guide them over the edge of the shoe bottom and are secured to supporting arms 162 mounted on pivot studs 164 which are secured to the outer ends of supporting members 166 fast on plates 168 on the side arms 28. The members 166 with the wipers 160 are adjustable laterally of the shoe along guideways formed in the plates 168 and are held in adjusted position by clamping bolts 170.
- 45 For depressing the arms 162 the plates 168 carry plungers 172 which are mounted in blocks 174, the latter having therein springs 176 which bear downwardly on the plungers and hold them normally at their lower limits of movement determined by engagement of their flanged heads with shoulders on the blocks 174. Light springs 178 connected to the arms 162 and to the plates 168 hold the arms 162 upwardly against the plungers 172, and the arms 162 with their wipers are thus positioned preferably to wipe the margin of the upper in over the bottom of the sole with comparatively light pressure upon the sole so as to avoid danger of displacing the margin of the sole in the overwiping operation. In such overwiping operation the wipers may yield upwardly against the pressure of the spring plungers 172 in response to resistance of the shoe materials. By means of screw and slot connections 180 (Fig. 1) the blocks 174 with their plungers 172 are adjustable on the plates 168 in order to position the wipers relatively to the plane of the shoe bottom to apply to the upper the degree of pressure desired.
- 50 To close the toe embracing wipers 154 laterally of the shoe in their movement lengthwise of the shoe, the arms 162 upon which the side wipers 160 are mounted are provided with forwardly extending fingers 182 (Fig. 9) for engagement with upwardly extending projections 184 on the ends of the wipers 154. It will be understood that in the movement of the front and side arms 26 and 28 inwardly toward the shoe the projections 184 on the toe wipers are carried into position to be engaged by the fingers 182 by the time when the wipers arrive substantially at the edge of the shoe bottom, and that in the continued movement of the wipers 154 lengthwise of the shoe they are closed inwardly by the fingers 182, simultaneously with the overwiping of the margin of the upper at the rear of the toe by the action of the side wipers 160. It will also be observed that the side wipers 160 have forward extensions beyond which the toe wipers advance, the toe and side wipers thus assuming what may be termed an interlocking relation to insure a continuity in the overlaying action of the different wipers upon the margin of the upper materials.
- 55 As hereinbefore explained, the gathering and overlaying of the margin of the upper about the toe end of the shoe is effected by the action of the toe embracing wipers 154 upon the elastic apron 34. The wipers arrive at the edge of the shoe bottom substantially at the time when the upwiping of the upper about the toe is completed. In order to prevent any further upward movement of the toe band during the overlaying operation of the wipers, the casing 46 is provided with depressions 186 to receive the ends of the cam extensions 140 and permit the extensions to turn idly in contact with the casing without swinging the casing about its pivotal 125
- 60 65 70 75 80 85 90 95 100 105 110 115 120 125 130
- 125 130

axis during continued forward movement of the front arm 26. Preferably also the cam plates 148 are so shaped as to impart no further upward movement to the apron holder 36 during the overlaying of the margin of the upper, the lower portion of the edges of said plates, beyond the point indicated at α , being substantially concentric with the axis of swinging movement of the front arm. It will be evident, however, that the upper portion of the apron 34 is carried inwardly over the bottom of the shoe by the member 36 during the overlaying operation of the wipers, such movement of the upper portion of the apron being continuous throughout the movement of the front arm 26, with the result that the apron, while held in its stretched condition, is drawn inwardly against the upper at the edge of the sole and is wrapped about said edge to bend the margin of the upper inwardly over the sole. As the toe wipers in their advancing and closing movements become effective upon the apron, they accentuate the over-wrapping or overlaying effect of the apron and press the apron inwardly at the sides of the toe, the wipers acting also to stretch that portion of the apron which is in engagement with the upper about the toe, thus rendering the apron further effective to draw the upper smoothly and tightly over the edge of the sole.

Similarly to the side wipers 160, the toe wipers 154 are so positioned relatively to the plane of the sole as to apply comparatively little downward pressure upon the sole in their inward movement, so as to avoid danger of displacing the sole on the last and also of pressing the margin of the upper prematurely into position to adhere to the sole. After the toe wipers and the side wipers have completed their inward movement over the shoe, they are forced downwardly to press the margin of the upper firmly into adhering relation to the sole. The downward movement of the toe wipers is effected by the action of a presser bar 188 on the front arm 26, the wipers being supported for the purpose of such movement upon a swinging holder 190 pivoted on the plate 42, and the downward movement of the side wipers is effected by presser bars 192 on the side arms 28, the several presser bars being operated and controlled in substantially the same manner as the tack driver bars of prior machines of this general type. It will be understood that the downward movement of the presser bars is effected by the action of spring impelled arms 194 (Fig. 1), the presser bars being normally upheld by the slide 30 and its connected parts which at the end of the inward movement of the front and side arms are rendered operative to release the bars. The controlling means for the front presser bar is shown in Fig. 2,

and comprises a block 196 on the presser bar which is engaged by a shoulder 198 on the slide 30. Fig. 3 illustrates the positions of the parts when the shoulder 198 has released the block 196 upon movement of the slide 30 relatively to the front arm, such action in the machine herein shown resulting from the engagement of a block 200 on the front arm with a stationary abutment 202 which limits the swinging movement of the arm. It will be understood that the side presser bars are similarly controlled, the inward movements of the side arms 28 being limited by abutments 204 (Fig. 6). When the front and side presser bars are thus released, they are forced yieldingly downward by the arms 194 and act upon the toe wiper plates 154 and upon the side wipers 160 to press the margin of the upper firmly into adhering relation to the sole. The front presser bar 188 is connected to the wiper holder 190 by links 206 for depressing and lifting the wipers through the movements of the bar. For depressing the side wipers the bars 192 carry blocks 208 which engage the arms 162 and force them downward, the arms being subsequently returned by the springs 178. It will be understood that in the return of the parts to starting position the front and side presser bars are lifted by the action of the slide 30 and its connected parts in substantially the same manner as the tack driver bars of prior machines, thus relieving the pressure of the wipers upon the shoe before the wipers are swung outwardly away from the shoe.

In order to avoid any danger of relaxing the pressure on the shoe when the slide 30 receives its movement relatively to the front arm 26 to release the presser bar 188, whereby the well-known yielding wedge connections between the slide and the front arm are rendered less effective to hold the arm in its inner position, the machine is provided with supplemental means for applying inwardly directed pressure to the arm 26. For this purpose there is pivotally mounted at 210 on the arm 26 a carrier 212 which has therein a spring plunger 214 arranged to bear upon the front face of the arm, and the slide 30 carries a roll 216 which bears upon a curved bar 218 secured on the side of the carrier 212. Since this supplemental pressure applying means is substantially like what is shown in Letters Patent No. 1,648,403, granted on my application on November 8, 1927, it need not be further described in detail. It will be understood that through this means adequate holding pressure upon the arm 26 is insured to maintain the wipers at the inner limit of their overwiping movement when the wipers are forced downwardly to press the upper upon the sole. Such supplemental holding means for the arm is particularly useful in the

present machine in view of the resistance of the elastic apron 34 against the wipers.

- As shown in Fig. 11, the sole rest comprises a pair of sole engaging feet 220 arranged to engage opposite side portions of the sole at the rear of the toe end and a third foot 222 for engaging the sole nearer the toe end of the shoe, the several feet being supported upon a carrier 224 (Fig. 10) 3) which, as hereinbefore explained, is rocked downwardly in the upper pulling operation by the cam 18. It has been found that in operating upon shoes of the type illustrated there is a tendency in the upper pulling operation to wrinkle the soft and yielding sole by the pressure of the several sole rest feet upon the sole. In the present construction there is accordingly provided means for straightening the sole by relative movement of the sole rest feet. To this end the side feet 220 are mounted on the front ends of arms 226 which are mounted in turn on pivot studs 228 in a bracket 230 which is fast on the carrier 224 (Fig. 3), and the front foot 222 is supported on a holder 232 which is mounted in the carrier 224 for sliding movement lengthwise of the shoe relatively to the bracket 230. A spring 234 tends as in prior constructions to move the holder 232 rearwardly, and for moving the holder forwardly against the resistance of the spring a pinion 236 is provided in engagement with rack teeth 238 on the holder, the pinion being fast on a shaft to which is secured a hand lever 240. Secured to the holder 232 is a plate 242 provided with a pin 244 which engages in slots 246 in the rear ends of the arms 226 and acts, when the holder is moved forwardly, to swing said arms in directions to separate the side feet 220. It will be evident therefore that by movement of the hand lever 240 after the machine has come to a stop with the upper under tension the front sole engaging foot 222 is moved forwardly toward the toe and the side feet are simultaneously moved apart toward the sides of the last to insure that the sole will lie flat upon the bottom of the last at the forepart.
- 50 In order to hold the sole engaging feet in the position to which they are moved by the hand lever 240, the shaft which carries the pinion 236 is provided (Fig. 12) with a ratchet wheel 248 which is engaged by a pawl 250. In order to cause the sole rest feet to be returned automatically to starting position by the action of the spring 234, the pawl 250 is controlled by a releasing member 252 carried by a slide 254 whereby, in machines of the illustrated type, the heel rest 20 is moved forwardly into engagement with the shoe. It will be understood that in the first period of the cycle the slide 254 is moved into position to permit the pawl to engage the ratchet wheel, and that

in the latter part of the final period of the cycle the slide is returned and renders the member 252 operative to swing the pawl into position to release the ratchet wheel, as shown in Fig. 12.

70 The means above described for straightening the sole by relative movement of the sole rest feet is not claimed herein, but in a divisional application Serial No. 184,394, filed on April 16, 1927.

75 In the operation of the machine, briefly summarized, the operator presents in the position illustrated in Fig. 2 a shoe, for example, of the type hereinbefore referred to, having the margin of its upper coated with cement, and then starts the machine, whereupon the toe and side grippers are closed in the well-known manner and pull the upper over the toe and the opposite sides of the forepart of the last. If controlled 80 in the manner customary heretofore in machines of this general type, the machine will then come to a stop with the upper held under tension, permitting the operator to inspect the work for any adjustment which 85 may be necessary. During this pause in the cycle of operations the operator may, if the character of the work renders it desirable, move the lever 240 to spread the sole rest members and thus insure that the sole will 90 lie flat upon the forepart of the last. Upon the subsequent starting of the machine, the side clamps are swung inwardly into engagement with the shoe, and simultaneously 95 the spring mechanism for applying the toe 100 band chain 44 and the flexible apron 34 about the toe is tripped by the latch 72. Immediately upon the application of the band about the toe and before any substantial movement of the wipers 154 toward the shoe, the toe gripper is tripped to release the upper. Following this operation the front 105 and side arms are swung inwardly toward the shoe, the front arm acting to raise the band chain 44 and the apron 34 to wipe the upper about the toe and at the same time to stretch the apron to increase its frictional drag on the upper. The upwiping movement of the apron ceases substantially at the 110 time when the apron is in the position illustrated in Fig. 5, the wipers 154 having then advanced substantially to the edge of the shoe bottom, and by continued movement of the front arm 26 the wipers are forced rearwardly over the toe in engagement with the 115 flexible apron while the apron is held in stretched condition by its supporting member 36, the latter moving rearwardly with the wipers to draw the apron inwardly over the shoe bottom.

120 Simultaneously with the movement of the front arm toward the shoe, the side arms 28 are swung inwardly and operate the side wipers 160 to lay the margin of the upper 125 over the sole at the sides of the forepart,

the side grippers being tripped to release the upper by the inward movement of the arms. As the side wipers are thus moved inwardly, the fingers 182 engage the projections 184 on the toe wipers and close the latter inwardly over the sides of the toe during their advancing movement lengthwise of the toe. During their advancing and closing movements the toe wipers 154 act upon the flexible apron 34 to press it inwardly from the end and side faces of the toe portion of the last and thus to gather and lay the margin of the upper inwardly over the sole, the wipers operating in such relation to the plane of the sole as to avoid pressing the margin of the upper prematurely into adhering relation to the bottom face of the sole. During this movement of the toe wipers they act frictionally on the elastic apron which is held in stretched condition between the toe band chain and the supporting member 36, and tend further to stretch the apron inwardly from the edge of the shoe bottom, thus tightening the apron over the edge of the sole and further insuring that the upper will be conformed smoothly and tightly to the contour of the last and to the sole along the edge of the shoe bottom. As the front arm is thus moved lengthwise of the shoe, the springs 68 apply progressively increasing pressure to the band chain 44 to assist in holding the upper about the periphery of the toe. When the front and side arms have arrived at their limits of movement, the pressure bars 188 and 192 are tripped, and the toe wipers and the side wipers are then forced downwardly to press the margin of the upper firmly into adhering relation to the sole. After this operation the parts are returned to starting position and the shoe is released.

Having described the invention, what I claim as new and desire to secure by Letters Patent of the United States is:

- 45 1. A machine of the class described having, in combination, means for pulling an upper over a last, overlaying means for laying the margin of the upper inwardly over the bottom of the last, a wiping device for engaging the upper continuously about the toe of the last from one side of the toe to the other side, and mechanism for operating said wiping device to wipe the upper heightwise of the last in time relation to the operation of the overlaying means.
- 50 2. A machine of the class described having, in combination, upper gripping means for pulling an upper over a last, overlaying means for laying the margin of the upper inwardly over the bottom of the last, means automatically operative in time relation to said overlaying means to cause the upper gripping means to release the upper, a wiping device for engaging the upper on the lateral periphery of the last, and mech-
- 55 anism for effecting relative movement between said wiping device and the last to wipe the upper heightwise of the last after the upper gripping means has released the upper. 70
- 60 3. A machine of the class described having, in combination, means for pulling an upper over a last, overlaying means movable inwardly to lay the margin of the upper over the bottom of the last, a wiping device for engaging the upper on the lateral periphery of the last, means for pressing said wiping device inwardly against the upper after the upper has been pulled, and mechanism automatically operative in time relation to the overlaying means to move said wiping device heightwise of the last to wipe the upper toward the edge of the last bottom. 75
- 65 4. A machine of the class described having, in combination, upper gripping means for pulling an upper over a last, overlaying means movable inwardly to lay the margin of the upper over the bottom of the last, a wiping device for engaging the upper continuously about the toe of the last from one side of the toe to the other side, mechanism for operating said wiping device to wipe the upper heightwise of the last, and means automatically operative in time relation to said wiping device to cause the upper gripping means to release the upper. 80
- 70 5. A machine of the class described having, in combination, upper gripping means for pulling an upper over a last, overlaying means for laying the margin of the upper inwardly over the bottom of the last, a wiping device for engaging the upper on the lateral periphery of the last, means for pressing said wiping device inwardly against the upper and for effecting in time relation to such application of pressure to the upper a release of the upper from the gripping means, and means for thereafter operating said wiping device and overlaying means in time relation to wipe the upper heightwise of the last and to lay its margin inwardly over the bottom of the last. 85
- 75 6. A machine of the class described having, in combination, upper gripping means for pulling an upper over a last, overlaying means for laying the margin of the upper inwardly over the bottom of the last, a wiping device for engaging the upper on the lateral periphery of the last, spring means arranged to be tripped to apply said wiping device to the upper, mechanism for tripping said spring means to render it operative, and mechanism for thereafter operating said wiping device and overlaying means in time relation to wipe the upper heightwise of the last and to lay its margin inwardly over the bottom of the last. 90
- 80 7. A machine of the class described having, in combination, upper gripping means 95

for pulling an upper over a last, overlaying means for laying the margin of the upper inwardly over the bottom of the last, a wiping device for engaging the upper on the lateral periphery of the last, spring means arranged to be tripped to apply said wiping device to the upper, mechanism for tripping said spring means to render it operative, means automatically operative in time relation to said tripping mechanism to release the upper from the gripping means, and means for imparting operative movements to said wiping device and overlaying means.

8. In a machine of the class described, the combination with last and shoe positioning means, of overlaying means movable toward the shoe to lay the margin of the upper over the sole, a wiping device for engaging the upper on the lateral periphery of the last, and mechanism automatically operative in the movement of said overlaying means toward the shoe to impart to said wiping device a wiping movement heightwise of the last.

9. In a machine of the class described, the combination with last and shoe positioning means, of overlaying means for laying the margin of the upper inwardly over the sole, a support for said overlaying means movable toward the shoe to carry said means over the bottom of the shoe, a wiping device carried by said support for engaging the upper on the lateral periphery of the last, and mechanism operated by the movement of said support toward the shoe for imparting to said wiping device a wiping movement heightwise of the last.

10. In a machine of the class described, the combination with last and shoe positioning means, of overlaying means for laying the margin of the upper inwardly over the sole, a support for said overlaying means movable toward the shoe to carry said means over the bottom of the shoe, a wiping device carried by said support for engaging the upper on the lateral periphery of the last, and mechanism automatically operative in the movement of said support toward the shoe to impart to said wiping device a wiping movement heightwise of the last and then to maintain said wiping device substantially stationary during continued movement of the support to carry the overlaying means over the sole.

11. In a machine of the class described, the combination with last and shoe positioning means, of overlaying means for laying the margin of the upper inwardly over the sole, a support for said overlaying means movable toward the shoe to carry said means over the bottom of the shoe, a wiping device carried by said support for engaging the upper on the lateral periphery of the last, and mechanism automatically operative in the movement of said support toward the shoe to ef-

fect a relative movement of said wiping device and the last to wipe the upper heightwise of the last.

12. In a machine of the class described, the combination with last and shoe positioning means, of overlaying means for laying the margin of the upper inwardly over the sole, a wiping device for engaging the upper on the lateral periphery of the last, spring means arranged to be tripped to apply said wiping device to the shoe, and operating means for effecting relative movement between the last and said wiping device and overlaying means to wipe the upper heightwise of the last and to lay its margin inwardly over the sole.

13. In a machine of the class described, the combination with last and shoe positioning means, of overlaying means for laying the margin of the upper inwardly over the sole, a wiping device for engaging the upper on the lateral periphery of the last, spring means for applying said wiping device to the shoe, a tripping device for releasing said spring means to render it operative, and means for thereafter imparting to said wiping device a wiping movement heightwise of the last in time relation to the operation of said overlaying means.

14. In a machine of the class described, the combination with last and shoe positioning means, of overlaying means for laying the margin of the upper inwardly over the sole, a support for said overlaying means movable toward the shoe to carry said means over the bottom of the shoe, a wiping device carried by said support for engaging the upper on the lateral periphery of the last, spring means for moving said wiping device relatively to its support to apply it to the shoe, a device for tripping said spring means to render it operative to apply said wiping device to the shoe, and mechanism automatically operative in time relation to the movement of said support toward the shoe to impart to said wiping device a wiping movement heightwise of the last.

15. In a machine of the class described, the combination with last and shoe positioning means, of overlaying means movable inwardly to lay the margin of the upper over the sole, a wiping device for engaging the upper on the lateral periphery of the last about the toe, and mechanisms automatically operative in time relation to the inward movement of said overlaying means to effect relative movement between said wiping device and the last to wipe the upper heightwise of the last and relative movement between said overlaying means and the shoe to press the margin of the upper upon the bottom face of the sole.

16. In a machine of the class described, the combination with last and shoe positioning means, of overlaying means movable in-

wardly to lay the margin of the upper over the sole, a wiping device for engaging the upper on the lateral periphery of the last, mechanism automatically operative in time relation to said overlaying means to impart to said wiping device a wiping movement heightwise of the last, and mechanism also automatically operative in time relation to the inward movement of said overlaying means to force said means toward the plane of the sole to press the margin of the upper on the sole.

17. A machine of the class described having, in combination, means for pulling an upper over a last, overlaying means for gathering the margin of the upper about an end of the last and for laying it inwardly over the bottom of the last, a wiping device for embracing the upper continuously about the end of the last, and mechanism for operating said wiping device in time relation to the overlaying means to wipe the upper heightwise of the last.

18. A machine of the class described having, in combination, means for gripping an upper on a last, a wiping device for embracing the upper continuously about the toe of the last, power operated means for effecting relative movement between the last and said gripping means to pull the upper and for moving the wiping device to wipe the upper heightwise of the last about the toe, and means for laying the margin of the upper about the toe inwardly over the bottom of the last.

19. A machine of the class described having, in combination, means for pulling an upper over a last, overlaying means comprising toe-embracing wipers for gathering and laying the margin of the upper about the toe inwardly over the bottom of the last, a wiping device for embracing the upper continuously about the toe, and mechanism automatically operative in time relation to said overlaying means to effect relative movement between the last and said wiping device to wipe the upper heightwise of the toe.

20. A machine of the class described having, in combination, a toe gripper, toe embracing wipers, a toe band, and operating mechanisms for effecting in automatically determined relation to one another relative movements between the last and said gripper and toe band and wipers to pull the upper, to wipe it heightwise of the last about the toe, and to lay its marginal portion inwardly over the bottom of the last.

21. A machine of the class described having, in combination, mechanism automatically operative to pull an upper over a last and to come to a stop with the upper held under tension, a wiping device for embracing the upper continuously about the toe of the last from one side of the toe to the other side, mechanism automatically operative

upon a subsequent starting of the machine to effect relative movement between the last and said wiping device to wipe the upper heightwise of the toe, and means for laying the margin of the upper about the toe inwardly over the bottom of the last.

22. A machine of the class described having, in combination, mechanism automatically operative to pull an upper over a last and to come to a stop with the upper held under tension, a wiping device for embracing the upper about the toe of the last, wipers for laying the margin of the upper about the toe inwardly over the bottom of the last, and means automatically operative upon a subsequent starting of the machine to impart operative movements to said wiping device and wipers to wipe the upper heightwise of the toe and to lay its margin inwardly over the bottom of the last.

23. A machine of the class described having, in combination, a toe gripper and means for operating it to pull an upper over the toe of a last, a wiping device and means for operating it to embrace the upper continuously about the toe and to wipe the upper heightwise of the toe, and means automatically operative in time relation to said wiping device to lay the margin of the upper about the toe inwardly over the bottom of the last.

24. A machine of the class described having, in combination, means for pulling an upper over a last, a wiping device for embracing the upper continuously about the toe of the last, automatic means for operating said wiping device to wipe the upper heightwise of the toe and for then maintaining said device in holding engagement with the upper, and means automatically operative while the upper is thus held to lay the margin of the upper about the toe inwardly over the bottom of the last.

25. A machine of the class described having, in combination, means for pulling an upper over a last, means for embracing the upper about the toe of the last and for wiping it heightwise of the last, mechanism automatically operative in time relation to said wiping means to cause the upper pulling means to release the upper prior to the wiping operation, and means for laying the margin of the upper about the toe inwardly over the bottom of the last.

26. A machine of the class described having, in combination, a toe gripper, mechanism for effecting relative movement between said gripper and a last to pull an upper over the last, a wiping device for embracing the upper about the toe, mechanism for effecting relative movement between said wiping device and the last to wipe the upper heightwise of the toe, tripping means automatically operative in time relation to said wiping device to cause the toe gripper to release the

upper prior to the wiping operation, and means for laying the margin of the upper inwardly over the bottom of the last.

27. A machine of the class described having, in combination, a toe gripper, a flexible toe band, power operated means for effecting relative movement between a last and said gripper and toe band to pull an upper and to wipe it heightwise of the last about the toe while the last is maintained in substantially the same position in the machine, and power means for releasing said toe gripper from the upper.

28. A machine of the class described having, in combination, a toe gripper, a flexible toe band, means for operating said gripper and toe band to pull an upper over a last and to wipe the upper heightwise of the last about the toe, and mechanism automatically operative to release said gripper from the upper in time relation to the wiping operation of the toe band.

29. A machine of the class described having, in combination, upper gripping means, mechanism for effecting relative movement between said upper gripping means and a last to pull an upper over the last, a wiping device for embracing the upper about the toe, mechanisms operative in time relation to apply said wiping device about the toe and to release the upper from the gripping means while the last is substantially in upper-pulling position, overlaying means, and means for effecting relative movement between the last and said wiping device and overlaying means to wipe the upper heightwise of the last and to lay its margin inwardly over the bottom of the last.

30. A machine of the class described having, in combination, means for pulling an upper over a last, a wiping device for embracing the upper about the toe of the last, spring means arranged to be tripped to apply said wiping device about the toe, and means for effecting relative movement between said wiping device and the last to wipe the upper heightwise of the toe.

31. A machine of the class described having, in combination, means for pulling an upper over a last, a wiping device for embracing the upper about the toe, spring means arranged to be tripped to apply said wiping device about the toe, mechanism automatically operative in time relation to the application of said wiping device to the toe to cause the upper pulling means to release the upper, and means for effecting relative movement between the last and said wiping device to wipe the upper heightwise of the toe.

32. A machine of the class described having, in combination, means for pulling an upper over a last, a wiping device for embracing the upper about the toe, spring means arranged to be tripped to apply said wiping

device about the toe, mechanism for effecting relative movement between said wiping device and the last to wipe the upper heightwise of the toe, and means for laying the margin of the upper about the toe inwardly over the bottom of the last.

33. A machine of the class described having, in combination, a toe gripper, a toe band, toe embracing wipers, spring means arranged to be tripped to apply said toe band about the toe, and means for thereafter operating said band and wipers to wipe the upper heightwise of the toe and to lay its margin inwardly over the bottom of the last.

34. A machine of the class described having, in combination, means automatically operative to pull an upper over a last and to come to a stop with the upper held under tension, a wiping device for embracing the upper about the toe, spring means arranged to be tripped to apply said wiping device to the toe, and mechanism automatically operative upon a subsequent starting of the machine to effect relative movement of said wiping device and the last to wipe the upper heightwise of the toe.

35. A machine of the class described having, in combination, means automatically operative to pull an upper over a last and to come to a stop with the upper held under tension, a toe band, spring means for applying said band about the toe, and mechanism automatically operative upon a subsequent starting of the machine to trip said spring means to render it operative to apply the band to the toe and to impart to said band a wiping movement heightwise of the toe.

36. A machine of the class described having, in combination, a toe gripper for pulling an upper over a last, a toe band, spring means for applying said band about the toe, and connected mechanisms for tripping said spring means to render it operative to apply the band and for tripping the toe gripper to cause it to release the upper.

37. In a machine of the class described, the combination with shoe positioning means, of a clamping device for embracing the shoe about the toe, spring means for applying said clamping device to the toe, and an automatically controlled latch for tripping said spring means to render it operative to apply said device to the toe.

38. In a machine of the class described, the combination with shoe end embracing wipers, of a clamping device for embracing the shoe about the toe, spring means for applying said clamping device about the toe, and mechanism automatically operative in time relation to said wipers to trip said spring means to render it operative to apply the clamping device to the toe.

39. In a machine of the class described, the combination with last and shoe position-

ing means, of a wiping device for embracing the upper about an end of the last, a support for said wiping device movable lengthwise of the shoe toward and from the shoe, and 5 mechanism operated by the movement of said support toward the shoe for imparting to said wiping device a wiping movement heightwise of the last.

40. In a machine of the class described, 10 the combination with last and shoe positioning means, of a toe band, a support for said toe band movable lengthwise of the shoe, spring means for moving the toe band relatively to its support to apply it about the 15 toe, and mechanism operated by movement of said support toward the shoe for imparting to said toe band a wiping movement heightwise of the toe.

41. In a machine of the class described, 20 the combination with last and shoe positioning means, of a wiping device for embracing the upper about the toe of the last, a support for said wiping device movable lengthwise of the shoe and on which said 25 wiping device is pivoted to swing about an axis extending laterally of the shoe, and mechanism operated by the movement of said support toward the shoe for swinging said wiping device about its axis to wipe the 30 upper heightwise of the toe.

42. In a machine of the class described, the combination with last and shoe positioning means, of a wiping device for embracing the upper about the toe of the last, 35 a support for said wiping device movable lengthwise of the shoe and on which said wiping device is pivoted to swing about an axis extending laterally of the shoe, a member pivoted on said support for swinging 40 said wiping device about its axis, and a relatively stationary abutment for operating said member in response to movement of the support toward the shoe to swing said wiping device to wipe the upper heightwise of 45 the toe.

43. In a machine of the class described, the combination with last and shoe positioning means, of a wiping device for embracing the upper about the toe of the last, 50 a support for said wiping device movable lengthwise of the shoe, mechanism automatically operative in the movement of said support toward the shoe to impart to said wiping device a wiping movement heightwise of the toe, 55 the toe, and spring means operated by said movement of the support for increasing the pressure of the wiping device upon the toe.

44. In a machine of the class described, the combination with last and shoe positioning means, of a wiping device for embracing the upper about the toe of the last, 60 a support for said wiping device movable lengthwise of the shoe, spring means operated by movement of said support toward the 65 shoe for increasing the pressure of the

wiping device upon the upper, and mechanism also operated by said movement of the support for imparting to the wiping device a wiping movement heightwise of the toe.

45. In a machine of the class described, 70 the combination with last and shoe positioning means, of a toe band, a support for said toe band movable lengthwise of the shoe, spring means arranged to be tripped to apply the band about the toe, mechanism arranged to act through said spring means in the movement of the support toward the shoe to increase the pressure of the band upon the toe, and mechanism automatically operative in said movement of the support 75 to impart to the band a wiping movement heightwise of the toe.

46. A machine of the class described having, in combination, a toe gripper for pulling an upper over a last, a front arm mounted for swinging movement lengthwise of the shoe, a wiping device carried by said front arm for embracing the upper about the toe, spring means arranged to be tripped to apply said wiping device about the toe, and 80 mechanism automatically operative in the swinging movement of said arm to impart to said wiping device a wiping movement heightwise of the toe.

47. A machine of the class described having, in combination, a toe gripper for pulling an upper over a last, a front arm mounted for swinging movement lengthwise of the shoe, a wiping device carried by said arm for embracing the upper about the toe, and 85 mechanism operated by the swinging movement of said arm toward the shoe for imparting to said wiping device a wiping movement heightwise of the toe.

48. A machine of the class described having, in combination, a toe gripper for pulling an upper over a last, a front arm mounted for swinging movement lengthwise of the shoe, a wiping device carried by said arm for embracing the upper about the toe, 90 mechanism controlled by the swinging movement of said arm toward the shoe for imparting to said wiping device a wiping movement heightwise of the toe, and mechanism operative in time relation to said wiping device to cause the toe gripper to release the upper.

49. In a machine of the class described, the combination with last and shoe positioning means, of a support movable lengthwise of the shoe, means on said support for laying the margin of the upper inwardly over the bottom of the last about the toe, a wiping device carried by said support for embracing the upper about the toe, and 100 mechanism automatically operative in the movement of said support toward the shoe to impart to said wiping device a wiping movement heightwise of the toe.

50. In a machine of the class described, 105

the combination with last and shoe positioning means, of a support movable lengthwise of the shoe, toe embracing wipers carried by said support for laying the margin of the upper inwardly over the bottom of the last 5
5 upper inwardly over the bottom of the last about the toe, a toe band also carried by said support, and mechanism for imparting to said toe band wiping movement heightwise of the toe in time relation to the overlaying movement of said wipers.

51. In a machine of the class described, the combination with last and shoe positioning means, of a support movable lengthwise of the shoe, means carried by said support 15
15 for laying the margin of the upper inwardly over the bottom of the last about the toe, a wiping device carried by said support for embracing the upper about the toe, and mechanism automatically operative in the 20
20 movement of said support toward the shoe to impart to said wiping device a wiping movement heightwise of the toe before said overlaying means becomes effective on the upper and then to hold said wiping device 25
25 from further wiping movement during the operation of said overlaying means upon the upper.

52. In a machine of the class described, the combination with last and shoe positioning means, of a support movable lengthwise of the shoe, means carried by said support for laying the margin of the upper inwardly over the bottom of the last about the toe, a toe band carried by said support 30
30 and mounted for swinging movement heightwise of the toe, and cam mechanism operated by the movement of said support toward the shoe to swing the toe band for wiping the upper heightwise of the toe and 35
35 then to hold the toe band from further wiping movement during the operation of said overlaying means upon the upper.

53. In a machine of the class described, the combination with last and shoe positioning means, of a wiping device for embracing the upper about the toe of the last, means for laying the margin of the upper about the toe inwardly over a sole on the bottom of the last, and operating mechanism for effecting in time relation relative movements between the last and said wiping device and overlaying means to wipe the upper heightwise of the toe and to lay the margin of the upper inwardly over the sole and press it into adhering relation to the sole.

54. A machine of the class described having, in combination, means for pulling an upper over a last, a wiping device for embracing the upper about the toe of the last, 60
60 means for effecting relative movement between the last and said wiping device to wipe the upper heightwise of the toe, means for laying the margin of the upper inwardly over a sole on the bottom of the last, and 65
65 operating mechanism for moving said over-

laying means inwardly over the sole and for effecting relative movement of said means and the last to press the margin of the upper into adhering relation to the bottom face of the sole.

55. A machine of the class described having, in combination, means for pulling an upper over a last, a wiping device for embracing the upper about the toe of the last, means for laying the margin of the upper 70
70 inwardly over a sole on the bottom of the last, and operating means for imparting to said wiping device a wiping movement heightwise of the toe and for then advancing said overlaying means over the bottom 75
75 of the sole and for moving it toward the plane of the sole to press the margin of the upper into adhering relation to the sole.

56. A machine of the class described having, in combination, means for pulling an 80
80 upper over a last, a toe band, toe embracing wipers, means for imparting to said toe band a wiping movement heightwise of the toe, and means for advancing and closing said wipers inwardly over the toe and for moving them toward the plane of the sole to press the margin of the upper into adhering relation to the sole.

57. A machine of the class described having, in combination, means for pulling an 85
85 upper over a last, a device for wiping the upper heightwise of the toe, toe embracing wipers, and operating mechanism for imparting to said wipers in time relation to the operation of said wiping device advancing and closing movement over the sole and movement toward the plane of the sole.

58. A machine of the class described having, in combination, means for pulling an upper over a last, a toe embracing wiping device and means for operating it to wipe the upper heightwise of the toe, toe embracing wipers, and operating mechanism for advancing and closing said wipers in time relation to the operation of said wiping device and for effecting substantially at the 100
100 end of the closing movement of the wipers a relative compressing movement of the wipers and the last to press the margin of the upper upon the sole.

59. A machine of the class described having, in combination, means for pulling an upper over a last, a wiper support movable lengthwise of the shoe, a wiping device carried by said support for embracing the upper about the toe of the last, mechanism automatically operative in the movement of said support toward the shoe to impart to said wiping device a wiping movement heightwise of the toe, toe embracing wipers 110
110 also carried by said wiper support for laying the margin of the upper inwardly over the sole about the toe, and mechanism automatically operative to effect relative movement of the wipers and the last in a direc- 115

130

tion transverse to the plane of the sole in time relation to the overlaying movement of the wipers.

60. A machine of the class described having, in combination, means for pulling an upper over a last, a wiper support movable lengthwise of the shoe, a wiping device carried by said support for embracing the upper about the toe of the last, mechanism automatically operative in the movement of said support toward the shoe to impart to said wiping device a wiping movement heightwise of the toe, toe embracing wipers carried by said support for laying the margin of the upper inwardly over the sole about the toe, said wipers being mounted for movement transversely of the plane of the sole, and mechanism automatically operative when said wipers have substantially completed their overlaying movement to force them toward the plane of the sole.

61. In a machine of the class described, the combination with last and shoe positioning means, of a flexible elastic apron arranged to engage the upper on the lateral periphery of the last, and means for effecting relative bodily movement of said apron and the last heightwise of the last to wipe the upper toward the edge of the last bottom and for simultaneously stretching said apron to increase its frictional drag on the upper.

62. In a machine of the class described, the combination with last and shoe positioning means, of a flexible elastic apron for engaging the upper on the lateral periphery of the last, supports for the opposite ends of said apron positioned respectively at opposite sides of the plane of the last bottom, and means for effecting relative bodily movement of said apron and the last heightwise of the last to wipe the upper toward the edge of the last bottom and for effecting relative movement of said supports to stretch the apron for increasing its frictional drag on the upper.

63. In a machine of the class described, the combination with last and shoe positioning means, of a flexible elastic apron for engaging the upper on the lateral periphery of the last, and means for effecting relative bodily movement of said apron and the last heightwise of the last to wipe the upper toward the edge of the last bottom and for stretching said apron and forcing it inwardly over the bottom of the last to lay the margin of the upper over the sole of the shoe.

64. In a machine of the class described, the combination with last and shoe positioning means, of a flexible elastic apron for engaging the upper on the lateral periphery of the last, a device for pressing said apron inwardly against the upper on the last, and means for effecting relative movement be-

tween said pressing device and the last to cause said apron to wipe the upper heightwise of the last, and means for simultaneously stretching said apron to increase its frictional drag on the upper.

65. In a machine of the class described, the combination with last and shoe positioning means, of a flexible elastic apron for engaging the upper on the lateral periphery of the last, a device for pressing said apron inwardly against the upper below the plane of the last bottom, means for effecting relative movement between said pressing device and the last to cause said apron to wipe the upper heightwise of the last, a member connected to said apron on the opposite side of the plane of the last bottom from said pressing device, and means for operating said member to stretch said apron and to draw the apron inwardly over the bottom of the last for laying the margin of the upper over the sole of the shoe.

66. In a machine of the class described, the combination with last and shoe positioning means, of a flexible apron for engaging the upper on the lateral periphery of the last, means for effecting relative bodily movement of said apron and the last heightwise of the last to wipe the upper toward the edge of the last bottom, and means for pressing said apron inwardly over the bottom of the last to lay the margin of the upper over the sole of the shoe.

67. In a machine of the class described, the combination with last and shoe positioning means, of a flexible apron for engaging the upper on the lateral periphery of the last, means for effecting relative movement of said apron and the last heightwise of the last to wipe the upper toward the edge of the last bottom, means for drawing said apron inwardly over the bottom of the last, and additional means for engaging said apron and pressing it inwardly over the bottom of the last to lay the margin of the upper over the sole of the shoe.

68. In a machine of the class described, the combination with last and shoe positioning means, of a flexible elastic apron for engaging the upper on the lateral periphery of the last, means for effecting relative movement between said apron and the last heightwise of the last to wipe the upper toward the edge of the last bottom and for stretching said apron to increase its frictional drag on the upper, and means for engaging said apron between its opposite ends while it is held in stretched condition and for pressing it inwardly over the bottom of the last to lay the margin of the upper over the sole of the shoe.

69. In a machine of the class described, the combination with last and shoe positioning means, of a flexible elastic apron for engaging the upper on the lateral periphery of

the last, means for stretching said apron heightwise of the last across the edge of the sole, and means for engaging the apron while it is held in stretched condition and for pressing it inwardly over the bottom of the last to lay the margin of the upper over the sole.

70. In a machine of the class described, the combination with last and shoe positioning means, of a flexible elastic apron for engaging the upper on the lateral periphery of the last, supports for the opposite ends of said apron positioned respectively at opposite sides of the plane of the last bottom, means for effecting relative movement between the last and said apron supports to cause the apron to wipe the upper heightwise of the last and for effecting relative movement of said supports to stretch the apron, and means for engaging said apron between its opposite ends and for pressing it inwardly over the bottom of the last to lay the margin of the upper over the sole of the shoe.

71. In a machine of the class described, the combination with last and shoe positioning means, of a flexible apron for engaging the upper on the lateral periphery of the last, an operating member connected to said apron, means for effecting relative movement between said member and the last to cause the apron to wipe the upper heightwise of the last, and means for engaging the apron between said member and the bottom of the last and for pressing the apron inwardly along the plane of the sole and toward said plane to lay the margin of the upper over the sole and press it into adhering relation to the sole.

72. In a machine of the class described, the combination with last and shoe positioning means, of a flexible elastic apron for engaging the upper on the lateral periphery of the last, means for effecting relative movement of said apron and the last to wipe the upper heightwise of the last and for stretching the apron inwardly over the edge of the last bottom, and additional means for engaging said apron and pressing it inwardly over the bottom of the last to lay the margin of the upper over the sole of the shoe.

73. In a machine of the class described, the combination with last and shoe positioning means, of a flexible elastic apron for engaging the upper on the lateral periphery of the last, means for stretching said apron heightwise of the last, and additional means for engaging the apron while it is held in stretched condition and for pressing it inwardly over the bottom of the last and toward the plane of the sole to lay the margin of the upper over the sole and press it upon the bottom face of the sole.

74. In a machine of the class described, the combination with last and shoe positioning means, of a flexible apron, supports for the

opposite ends of said apron positioned respectively at opposite sides of the plane of the last bottom, means for engaging the apron between said supports and for pressing the apron inwardly over the bottom of the last to lay the margin of the upper over the sole of the shoe, and mechanism for effecting relative movement of said apron engaging means and the last in a direction transverse to the plane of the sole to press the margin of the upper upon the bottom face of the sole.

75. In a machine of the class described, the combination with last and shoe positioning means, of a flexible elastic apron, supports for the opposite ends of said apron, means for effecting relative movement of said supports to stretch the apron heightwise of the last, and means for engaging said apron between its opposite ends and for pressing it inwardly over the bottom of the last to lay the margin of the upper over the sole of the shoe.

76. In a machine of the class described, the combination with last and shoe positioning means, of a flexible apron arranged to extend heightwise of the shoe, supports for said apron positioned respectively at opposite sides of the plane of the last bottom, means for engaging the apron between its supports and for pressing it inwardly over the bottom of the last to lay the margin of the upper over the sole, and mechanism for effecting relative movement between said apron engaging means and the last in a direction transverse to the plane of the sole to cause the apron to press the margin of the upper upon the bottom face of the sole.

77. In a machine of the class described, the combination with last and shoe positioning means, of a flexible apron for engaging the upper on the lateral periphery of the last, means for pressing said apron inwardly against the upper on the last, a member connected to said apron on the opposite side of the plane of the last bottom from said pressing means, and means for engaging the apron between said member and the bottom of the last and for pressing the apron inwardly over the bottom of the last to lay the margin of the upper over the sole of the shoe.

78. In a machine of the class described, the combination with last and shoe positioning means, of a flexible elastic apron for engaging the upper on the lateral periphery of the last, means for pressing said apron inwardly against the upper on the last, a member connected to said apron on the opposite side of the plane of the last bottom from said pressing means, means for operating said member to stretch the apron, and means for engaging said apron and for pressing it inwardly over the bottom of the last while it is held in stretched condition.

to lay the margin of the upper over the sole of the shoe.

79. In a machine of the class described, the combination with last and shoe positioning means, of a flexible apron for engaging the upper on the lateral periphery of the last, a member for pressing said apron inwardly against the upper on the last, means for effecting relative movement between said member and the last to cause the apron to wipe the upper heightwise of the last, and means for pressing said apron inwardly over the bottom of the last to lay the margin of the upper over the sole of the shoe.

80. In a machine of the class described, the combination with last and shoe positioning means, of a flexible elastic apron for engaging the upper on the lateral periphery of the last, members connected to said apron respectively at opposite sides of the plane of the last bottom, means for operating one of said members to press the apron inwardly against the upper on the last, means for effecting relative movement between said members and the last to cause the apron to wipe the upper heightwise of the last and to stretch the apron, and means for engaging the apron and pressing it inwardly over the bottom of the last to lay the margin of the upper over the sole of the shoe.

81. In a machine of the class described, the combination with last and shoe positioning means, of a flexible apron for engaging the upper on the lateral periphery of the last, means for effecting relative bodily movement of said apron and the last to wipe the upper heightwise of the last, and mechanism automatically operative in time relation to said relative wiping movement of the apron and the last to press the apron inwardly over the bottom of the last for laying the margin of the upper over the sole.

82. In a machine of the class described, the combination with last and shoe positioning means, of a flexible apron for engaging the upper on the lateral periphery of the last, supporting members connected to the opposite ends of said apron and positioned respectively at opposite sides of the plane of the last bottom, means for effecting relative movement between said members and the last to cause the apron to wipe the upper heightwise of the last, a device for engaging the apron between its opposite ends, and means for operating said apron engaging device in time relation to the upwiping operation of the apron to press the apron inwardly over the bottom of the last for laying the margin of the upper over the sole.

83. In a machine of the class described, the combination with last and shoe positioning means, of a flexible apron for engaging the upper on the lateral periphery of the last, a supporting member and means for operating it to pull the apron heightwise of

the last in wiping engagement with the upper, a device for engaging the apron between said member and the plane of the last bottom, and means for operating said apron engaging device in time relation to said supporting member to press the apron inwardly over the bottom of the last for laying the margin of the upper over the sole.

84. In a machine of the class described, the combination with last and shoe positioning means, of a flexible apron for engaging the upper on the lateral periphery of the last, means for effecting relative movement of said apron and the last to wipe the upper heightwise of the last, an overlaying device for engaging said apron, and means for moving said overlaying device inwardly over the bottom of the last to cause the apron to lay the margin of the upper over the sole and for effecting in time relation to the inward movement of said overlaying device a relative movement between said device and the last transversely of the plane of the sole to press the margin of the upper upon the bottom face of the sole.

85. In a machine of the class described, the combination with last and shoe positioning means, of a flexible elastic apron for engaging the upper on the lateral periphery of the last, means for effecting relative movement of said apron and the last to wipe the upper heightwise of the last and to stretch the apron, an overlaying device for engaging said apron, and means for operating said overlaying device in time relation to the upwiping operation of the apron and while the apron is held in stretched condition to force the apron inwardly over the bottom of the last for laying the margin of the upper over the sole.

86. In a machine of the class described, the combination with last and shoe positioning means, of a flexible apron for embracing the upper about an end of the last, means for drawing said apron inwardly over the bottom of the last across the edge of the sole of the shoe, and additional means for engaging said apron and pressing it inwardly about the end of the last to lay the margin of the upper over the sole.

87. In a machine of the class described, the combination with last and shoe positioning means, of a flexible apron for embracing the upper about an end of the last, means for drawing said apron inwardly over the bottom of the last across the edge of the sole of the shoe, overlaying means for engaging said apron to lay the margin of the upper inwardly over the sole about the end of the shoe, and operating mechanism for effecting relative movement between said overlaying means and the last transversely of the plane of the sole to press the margin of the upper into adhering relation to the sole.

88. In a machine of the class described, the combination with last and shoe positioning means, of a flexible apron for embracing the upper about an end of the last, 5 means for drawing said apron inwardly over the bottom of the last across the edge of the sole of the shoe, end embracing wipers, and means for advancing and closing said wipers in engagement with the apron to 10 gather the margin of the upper and to lay it inwardly over the sole.
89. In a machine of the class described, the combination with last and shoe positioning means, of a flexible apron for embracing the upper about an end of the last, 15 clamping means for embracing the end of the shoe to press the apron against the upper on the last, means for pressing the apron inwardly over the bottom of the last about 20 the end of the shoe to lay the margin of the upper over the sole, and means for pulling on the apron in a direction transverse to the plane of the sole to hold the apron tight as it is pressed inwardly over the sole.
90. In a machine of the class described, 25 the combination with last and shoe positioning means, of a flexible apron for embracing the upper about an end of the last, clamping means for embracing the end of the shoe to press the apron against the upper on the last, a support connected to 30 said apron on the opposite side of the plane of the shoe bottom from said clamping means, and overlaying means arranged to 35 engage the apron between said support and the plane of the shoe bottom and to press the apron inwardly over the bottom of the last about the end of the shoe to lay the margin of the upper over the sole.
91. In a machine of the class described, 40 the combination with last and shoe positioning means, of a flexible apron for embracing the upper about an end of the last, clamping means for embracing the end of the shoe to press the apron against the upper 45 on the last, means connected to said apron on the opposite side of the plane of the shoe bottom from said clamping means to hold the apron tight across the edge of the 50 shoe bottom, end embracing wipers, and means for operating said wipers to press the apron inwardly over the bottom of the last about the end of the shoe for laying the margin of the upper over the sole.
92. In a machine of the class described, 55 the combination with last and shoe positioning means, of a flexible apron for embracing the upper about an end of the last, clamping means for embracing the end of the shoe to press the apron against the upper 60 on the last, end embracing wipers and means for operating them to press said apron inwardly over the bottom of the last about the end of the shoe for laying the 65 margin of the upper over the sole, and sup-

porting means connected to the apron and movable to carry a portion of the apron inwardly over the bottom of the last during the operation of the wipers.

93. In a machine of the class described, 70 the combination with last and shoe positioning means, of a flexible apron for embracing the upper about an end of the last, a wiper support movable lengthwise of the shoe, end embracing wipers on said support for engaging the apron to lay the margin of the upper about the end of the shoe inwardly over the sole, and means on said wiper support connected to the apron to draw it inwardly over the bottom of the last during 75 the operation of the wipers.

94. In a machine of the class described, 80 the combination with last and shoe positioning means, of a flexible apron for embracing the upper about an end of the last, end embracing wipers for engaging the apron to lay the margin of the upper about the end of the shoe inwardly over the sole, a support for said wipers movable to advance them over the shoe bottom, and members on said 85 wiper support connected to the apron respectively at opposite sides of the plane of the wipers for controlling the apron during the overlaying operation.

95. In a machine of the class described, 90 the combination with last and shoe positioning means, of a flexible apron for embracing the upper about an end of the last, a wiper support movable lengthwise of the shoe, end 95 embracing wipers on said support for engaging the apron to lay the margin of the upper about the end of the shoe inwardly over the sole, means on said wiper support for pressing the apron inwardly against the upper about the end of the last, and a member 100 on said wiper support connected to the apron at the opposite side of the wipers from the plane of the shoe bottom for holding the apron tight during the overlaying operation of the wipers.

96. In a machine of the class described, 105 the combination with last and shoe positioning means, of a flexible apron for embracing the upper about an end of the last, a wiper support movable lengthwise of the shoe, end 110 embracing wipers on said support for engaging the apron to lay the margin of the upper about the end of the shoe inwardly over the sole, clamping means on said wiper support for pressing the apron inwardly against the upper about the end of the last, and spring means arranged to be tripped to apply said clamping means about the end 115 of the shoe prior to the operation of the wipers.

97. In a machine of the class described, 120 the combination with last and shoe positioning means, of a flexible apron for embracing the upper about an end of the last, operating means for effecting relative move- 125

ment between the last and said apron to wipe the upper heightwise of the last, means for drawing the apron inwardly over the bottom of the last across the edge of the 5 sole of the shoe, and overlaying means for pressing said apron inwardly over the bottom of the last about the end of the shoe to lay the margin of the upper over the sole.

98. In a machine of the class described, 10 the combination with last and shoe positioning means, of a flexible apron for embracing the upper about an end of the last, means for effecting relative movement between 15 said apron and the last to wipe the upper heightwise of the last, clamping means for 20 pressing said apron inwardly against the upper about the end of the last, and means for operating on the apron while it is held by said clamping means to lay the margin 25 of the upper about the end of the shoe inwardly over the sole.

99. In a machine of the class described, the combination with last and shoe positioning means, of a flexible apron for embracing the 25 upper about an end of the last, clamping means for pressing said apron inwardly against the upper about the end of the last, means for effecting relative movement between the last and said clamping means to 30 cause the apron to wipe the upper heightwise of the last, end embracing wipers, and means for operating said wipers to press the apron inwardly over the bottom of the last about the end of the shoe for laying the 35 margin of the upper over the sole while said clamping means is applied about the end of the last.

100. In a machine of the class described, the combination with last and shoe positioning 40 means, of a wiper support mounted for movement lengthwise of the shoe, a flexible apron carried by said wiper support for embracing the upper about an end of the last, means for effecting relative movement be- 45 tween said apron and the last to wipe the upper heightwise of the last, and wipers on said support for engaging the apron and pressing it inwardly over the bottom of the last about the end of the shoe to lay the 50 margin of the upper over the sole.

101. In a machine of the class described, the combination with last and shoe positioning means, of a wiper support mounted for movement lengthwise of the shoe, a flexible 55 apron carried by said wiper support for embracing the upper about an end of the last, a clamping device on said wiper support for pressing the apron inwardly against the upper about the end of a last, means for 60 effecting relative movement between the last and said clamping device to cause the apron to wipe the upper heightwise of the last, and wipers on said support for pressing the apron inwardly over the bottom of the last 65 to lay the margin of the upper over the sole.

102. In a machine of the class described, the combination with last and shoe positioning means, of a wiper support mounted for movement lengthwise of the shoe, a flexible apron carried by said wiper support for embracing the upper about an end of the last, 70 mechanism operated by the movement of said wiper support toward the shoe for imparting to said apron wiping movement heightwise of the shoe, and wipers on said 75 support for pressing the apron inwardly over the bottom of the last about the end of the shoe to lay the margin of the upper over the sole.

103. In a machine of the class described, 80 the combination with last and shoe positioning means, of a wiper support mounted for movement lengthwise of the shoe, a flexible apron carried by said wiper support for embracing the upper about an end of the last, 85 members connected to said apron respectively at opposite sides of the plane of the shoe bottom, mechanism for operating said members in the movement of the wiper support toward the shoe to impart to said apron a 90 wiping movement heightwise of the last, and wipers on said support for pressing the apron inwardly over the bottom of the last about the end of the shoe to lay the margin 95 of the upper over the sole.

104. In a machine of the class described, the combination with last and shoe positioning means, of a wiper support mounted for movement lengthwise of the shoe, a flexible apron carried by said wiper support for embracing the upper about an end of the last, a clamping device carried by said support for pressing said apron inwardly against the upper about the end of the last, spring means arranged to be tripped to apply said clamping device to the shoe, mechanism operative in the movement of said wiper support toward the shoe to impart to said clamping device and apron a wiping movement heightwise of the last, and wipers on said 100 support for pressing said apron inwardly over the bottom of the last about the end of the shoe to lay the margin of the upper over the sole.

105. In a machine of the class described, 115 the combination with last and shoe positioning means, of a flexible elastic apron for embracing the upper about an end of the last, and means for effecting relative bodily movement of said apron and the last heightwise 120 of the last to wipe the upper about the end of the shoe toward the edge of the last bottom and for simultaneously stretching said apron to increase its frictional drag on the upper.

106. In a machine of the class described, the combination with last and shoe positioning means, of a flexible elastic apron for embracing the upper about an end of the last, 125 supports for the opposite ends of said apron 130

- positioned respectively at opposite sides of the plane of the last bottom for holding the apron about the end of the last, and means for effecting relative movement between the last and said supports to cause the apron to wipe the upper heightwise of the last and for simultaneously effecting relative movement of said supports to stretch the apron for increasing its frictional drag upon the upper.
107. In a machine of the class described, the combination with last and shoe positioning means, of a flexible elastic apron for embracing the upper about an end of the last, a clamp for pressing said apron inwardly about the end of the last, means for effecting relative movement of the last and said clamp and apron to wipe the upper heightwise of the last, a member connected to said apron on the opposite side of the plane of the last bottom from said clamp, and means for operating said member to stretch the apron during the relative wiping movement of the last and the clamp.
108. In a machine of the class described, the combination with last and shoe positioning means, of a flexible elastic apron for embracing the upper about an end of the last, means for stretching said apron about the end of the last and inwardly over the edge of the last bottom, and means for pressing said apron inwardly about the end of the last to lay the margin of the upper over the sole while the apron is held in stretched condition.
109. In a machine of the class described, the combination with last and shoe positioning means, of a flexible elastic apron for embracing the upper about an end of the last, members connected to the opposite ends of said apron respectively at opposite sides of the plane of the last bottom for stretching the apron over the edge of the last bottom, and means for engaging the apron between said members and for pressing the apron inwardly about the end of the shoe to lay the margin of the upper over the sole.
110. In a machine of the class described, the combination with last and shoe positioning means, of a flexible elastic apron for embracing the upper about an end of the last, a clamping device for pressing the apron inwardly against the upper about the end of the last, means for carrying a portion of the apron inwardly over the last bottom and for stretching the apron while it is held clamped about the end of the last, and means for pressing the apron inwardly over the bottom of the last about the end of the shoe to lay the margin of the upper over the sole.
111. In a machine of the class described, the combination with last and shoe positioning means, of a flexible elastic apron for embracing the upper about an end of the last, a clamping device for pressing said apron inwardly against the upper about the end of the last, a support connected to the apron on the opposite side of the plane of the last bottom from said clamping device for holding the apron, and means for engaging the apron between said clamping device and support and for pressing the apron inwardly and stretching it to lay the upper over the sole about the end of the shoe.
112. In a machine of the class described, the combination with last and shoe positioning means, of a flexible elastic apron for embracing the upper about an end of the last, members connected to the opposite ends of said apron, means for effecting relative movement of said members to stretch the apron over the edge of the shoe bottom, end embracing wipers for engaging the apron between said members, and means for operating said wipers to press the apron inwardly over the bottom of the last about the end of the shoe for laying the margin of the upper over the sole.
113. In a machine of the class described, the combination with last and shoe positioning means, of a flexible elastic apron for embracing the upper about an end of the last, means for effecting relative movement of the last and said apron to wipe the upper heightwise of the last and for stretching the apron to increase its frictional drag on the upper, end embracing wipers, and means for operating said wipers to press the apron inwardly over the bottom of the last about the end of the shoe for laying the margin of the upper over the sole and for then effecting relative movement of the wipers and the last transversely of the plane of the shoe bottom to press the upper into adhering relation to the sole.
114. In a machine of the class described, the combination with last and shoe positioning means, of a wiper support movable lengthwise of the shoe, a flexible elastic apron carried by said wiper support for embracing the upper about an end of the last, mechanism automatically operative in the movement of said support toward the shoe to impart to said apron a wiping movement heightwise of the last and to stretch the apron, and wipers carried by said support for pressing the apron inwardly over the bottom of the last about the end of the shoe to lay the margin of the upper over the sole.
115. In a machine of the class described, the combination with last and shoe positioning means, of a wiper support movable lengthwise of the shoe, a flexible elastic apron carried by said wiper support for embracing the upper about an end of the last, mechanism automatically operative in the movement of said wiper support toward the shoe to impart to said apron a wiping movement heightwise of the last and to stretch the apron, end embracing wipers on said support, means for imparting closing movement

- to said wipers during their advancing movement over the shoe to press the apron inwardly about the end of the shoe for laying the margin of the upper over the sole, and mechanism automatically operative in time relation to the movement of said wiper support to press said wipers toward the plane of the sole.
116. In a machine of the class described, the combination with last and shoe positioning means, of a wiper support movable lengthwise of the shoe, a flexible elastic apron carried by said wiper support for embracing the upper about an end of the last, a clamping device on said support for clamping the apron against the upper about the end of the last, end embracing wipers on said support for pressing the apron inwardly over the bottom of the last to lay the margin of the upper over the sole, and a member on said support for carrying a portion of the apron inwardly over the shoe bottom with the wipers and for holding the apron tight during the operation of the wipers.
117. In a machine of the class described, the combination with last and shoe positioning means, of a wiper support movable lengthwise of the shoe, a flexible apron for embracing the upper about an end of the last, members connected to the opposite ends of said apron, and cam means automatically operative in the movement of the wiper support toward the shoe to impart to the apron through said members a wiping movement heightwise of the shoe.
118. In a machine of the class described, the combination with last and shoe positioning means, of a wiper support movable lengthwise of the shoe, a flexible elastic apron carried by said wiper support for embracing the upper about an end of the last, a clamping device for clamping said apron against the upper about the end of the last, mechanism operated by movement of said wiper support toward the shoe for imparting to said clamping device a wiping movement heightwise of the shoe, a member connected to the apron on the opposite side of the plane of the shoe bottom from said clamping device, and mechanism automatically operative in said movement of the wiper support to impart to said member a movement in the same direction as the clamping device and of greater extent than the clamping device for stretching the apron.
119. In a machine of the class described, the combination with last and shoe positioning means, of a wiper support movable lengthwise of the shoe, a flexible apron carried by said wiper support for embracing the upper about an end of the last, wipers on said support for pressing said apron inwardly over the bottom of the last about the end of the shoe to lay the margin of the upper over the sole, supporting members connected to the opposite ends of said apron, and mechanism operated and controlled by movement of said wiper support toward the shoe for imparting to the apron through said members a wiping movement heightwise of the shoe and for then holding said apron from further wiping movement during the operation of the wipers upon the apron.
120. A machine of the class described having, in combination, means for pulling an upper over a last, a flexible apron for engaging the upper on the lateral periphery of the last and for laying the margin of the upper inwardly over the bottom of the last, and means for effecting relative movement of the last and said apron to wipe the upper heightwise of the last and to lay its margin inwardly.
121. A machine of the class described having, in combination, means for gripping the margin of an upper on a last, a flexible apron for embracing the upper about the toe end of the last and for gathering and laying the margin of the upper inwardly over the bottom of the last, and operating means for effective relative movement between the last and said gripping means and apron to pull the upper and to wipe it heightwise of the last and lay its margin inwardly about the toe.
122. A machine of the class described having, in combination, means for gripping the margin of an upper on a last, a flexible apron for engaging the upper on the lateral periphery of the last, said apron comprising a sheet of flexible material arranged to extend beyond the edge of the last bottom for laying the upper inwardly over an insole on the last, and operating mechanism organized to effect in sequence through said upper gripping means and apron a pulling of the upper over the last and a wiping of the upper heightwise of the last.
123. A machine of the class described having, in combination, a gripper for pulling an upper over a last, a flexible apron for engaging the upper on the lateral periphery of the last, means for effecting relative movement of the last and said apron to wipe the upper heightwise of the last and for stretching the apron in the direction of the wipe, and mechanism automatically operative in time relation to said relative wiping movement to release the gripper from the upper.
124. A machine of the class described having, in combination, a toe gripper for pulling an upper over a last, a flexible apron for embracing the upper about the toe of the last, mechanisms automatically operative in time relation to each other to apply said apron about the toe and to release the toe gripper from the upper, and means for

- effecting relative movement of the last and said apron to wipe the upper heightwise of the toe and for stretching the apron in the direction of the wipe.
- 5 125. A machine of the class described having, in combination, a toe gripper for pulling an upper over a last, a flexible apron for embracing the upper about the toe of the last, means for advancing said apron toward the toe and for moving it heightwise of the toe in wiping engagement with the upper, and mechanism automatically operative in time relation to said apron to release the toe gripper from the upper.
- 10 126. A machine of the class described having, in combination, upper gripping means for pulling an upper over a last, a flexible apron for embracing the upper about the toe of the last, a clamping device and means for operating it to clamp the apron about the toe while the upper is held by the gripping means, and means engaging the apron independently of said clamping device and co-operating with said device for thereafter moving said apron heightwise of the toe in wiping engagement with the upper.
- 15 127. A machine of the class described having, in combination, means automatically operative to pull an upper over a last and to come to a stop with the upper held under tension, a flexible apron for embracing the upper about the toe of the last, and mechanisms automatically operative upon a subsequent starting of the machine to move said apron heightwise of the last in wiping engagement with the upper and to release the upper pulling means from the upper.
- 20 128. A machine of the class described having, in combination, a toe gripper for pulling an upper over a last, a flexible apron for embracing the upper about the toe of the last, spring means arranged to be tripped to apply said apron about the toe, mechanisms operative in time relation to each other to trip said spring means and to release the toe gripper from the upper and means for thereafter effecting relative movement of the last and said apron to wipe the upper heightwise of the toe.
- 25 129. A machine of the class described having, in combination, means for pulling an upper over a last, a flexible elastic apron for engaging the upper on the lateral periphery of the last, and means for imparting to said apron after the upper has been pulled a wiping movement heightwise of the last and for stretching the apron to increase its frictional drag on the upper.
- 30 130. A machine of the class described having, in combination, means for pulling an upper over a last, a flexible apron for engaging the upper on the lateral periphery of the last, means for effecting relative movement of the last and said apron to wipe the upper heightwise of the last after the upper
- has been pulled, and means for pressing said apron inwardly over the bottom of the last to lay the margin of the upper over the sole of the shoe.
- 35 131. A machine of the class described having, in combination, upper gripping means for pulling an upper over a last, a flexible elastic apron for embracing the upper about the toe, means for applying said apron to the toe and for holding it tight across the edge of the shoe bottom, and means for pressing the apron inwardly about the toe while it is thus held to lay the margin of the upper over the sole.
- 40 132. A machine of the class described having, in combination, means for pulling an upper over a last, a flexible apron for embracing the upper about the toe of the last, operating mechanism for effecting relative movement between the last and said flexible apron to wipe the upper heightwise of the toe and to lay the margin of the upper inwardly over the bottom of the last, and mechanism automatically operative in time relation to said relative wiping movement to cause the upper pulling means to release the upper.
- 45 133. A machine of the class described having, in combination, a toe gripper for pulling an upper over the toe of a last, a flexible apron for embracing the upper about the toe, toe embracing wipers mounted for movement toward the toe and arranged to act upon the upper through said apron, means for applying said apron to the toe and for releasing the toe gripper from the upper prior to any substantial movement of the wipers toward the toe, and means for operating the wipers to press said apron inwardly about the toe to lay the margin of the upper over the sole of the shoe.
- 50 134. A machine of the class described having, in combination, a toe gripper for pulling an upper over a last, a flexible apron for embracing the upper about the toe, means for applying said apron to the toe and for releasing the toe gripper from the upper, toe embracing wipers arranged to act upon the upper through said apron, and means for advancing and closing said wipers to lay the margin of the upper over the sole of the shoe and for effecting relative movement between said wipers and the last to press the upper into adhering relation to the sole.
- 55 135. A machine of the class described having, in combination, a toe gripper for pulling an upper over a last, a flexible apron for embracing the upper about the toe, mechanisms automatically operative in time relation to each other to apply said apron about the toe and to release the toe gripper from the upper, toe embracing wipers arranged to act upon the upper through said apron, and means for operating the apron to wipe the upper heightwise of the toe and for operat-

ing said wipers to lay the margin of the upper inwardly over the sole of the shoe.

136. A machine of the class described having, in combination, a toe gripper for pulling an upper over a last, a flexible elastic apron for embracing the upper about the toe, means for applying said apron about the toe and for stretching it across the edge of the sole of the shoe, means for releasing the toe gripper from the upper, toe embracing wipers arranged to act on the upper through said apron, means for advancing and closing said wipers about the toe to lay the margin of the upper over the sole while the apron is held in stretched condition, and means for effecting relative movement of said wipers and the last to press the upper into adhering relation to the sole.

137. A machine of the class described having in combination, a toe gripper for pulling an upper over a last, a flexible apron for embracing the upper about the toe, means for applying said apron to the toe and for moving it heightwise of the toe in wiping engagement with the upper, means for releasing the toe gripper from the upper, toe embracing wipers arranged to act upon the upper through said apron, and means for advancing and closing said wipers to lay the margin of the upper about the toe inwardly over the sole.

138. A machine of the class described having, in combination, a toe gripper for pulling an upper over a last, a flexible elastic apron for embracing the upper about the toe, a clamping device and means for operating it to clamp the apron about the toe while the upper is held by the gripper, mechanism automatically operative after the apron has been clamped about the toe to release the toe gripper from the upper, means for effecting relative movement between the last and said apron to wipe the upper heightwise of the toe, toe embracing wipers arranged to act upon the upper through said apron, and means for advancing and closing said wipers to lay the margin of the upper about the toe inwardly over the sole.

139. A machine of the class described having, in combination, a toe gripper for pulling an upper over a last, a flexible elastic apron for embracing the upper about the toe, means for applying said apron about the toe while the upper is held by the toe gripper and for thereafter releasing said gripper from the upper, means for moving said apron heightwise of the toe in wiping engagement with the upper and for stretching the apron, toe embracing wipers arranged to act on the upper through said apron, means for advancing and closing said wipers to lay the margin of the upper over the sole, and mechanism automatically operative in time relation to the advancing and closing movement of the

wipers to move said wipers toward the plane of the sole for pressing the margin of the upper into adhering relation to the sole.

140. A machine of the class described having, in combination, a toe gripper for pulling an upper over a last, a flexible apron for embracing the upper about the toe, a wiper support mounted for movement toward the toe, toe embracing wipers carried by said support and arranged to act on the upper though said apron to lay the margin of the upper over the sole of the shoe, and mechanism automatically operative in the movement of said wiper support toward the toe to impart to said apron a wiping movement heightwise of the toe.

141. A machine of the class described having, in combination, a toe gripper for pulling an upper over a last, a flexible elastic apron for embracing the upper about the toe, a front arm mounted for swinging movement toward the toe, a clamping device carried by said arm for clamping said apron against the upper about the toe, mechanism operated by movement of said arm toward the toe for imparting to said clamping device and apron a wiping movement heightwise of the toe, and toe embracing wipers carried by said arm for pressing the apron inwardly over the bottom of the last about the toe to lay the margin of the upper over the sole.

142. A machine of the class described having, in combination, a toe gripper for pulling an upper over a last, a front arm mounted for swinging movement toward the toe, a flexible elastic apron carried by said arm for embracing the upper about the toe, mechanisms automatically operative in time relation to each other to apply said apron to the toe and to release the toe gripper from the upper, toe embracing wipers carried by said arm and arranged to act upon the upper through said apron, and mechanism automatically operative in the movement of said arm toward the toe to impart to said apron a wiping movement heightwise of the toe prior to the overlaying movement of the wipers.

143. A machine of the class described having, in combination a toe gripper for pulling an upper over a last, a front arm mounted for swinging movement toward the toe, a flexible elastic apron carried by said arm, spring means on said arm for pressing said apron inwardly about the toe, means automatically operative to trip said spring means for applying the apron to the toe and for releasing the toe gripper from the upper, and toe embracing wipers carried by said arm and arranged to act on the upper through said apron to lay the margin of the upper inwardly over the sole.

144. A machine of the class described having, in combination, a toe gripper for pulling

- an upper over a last, a front arm mounted for swinging movement toward the toe, a flexible elastic apron carried by said arm, spring means on said arm for applying said apron about the toe, mechanisms automatically operative in time relation to trip said spring means for applying the apron to the toe and for releasing the toe gripper from the upper, means operated by movement of said arm toward the toe for imparting to said apron a wiping movement heightwise of the toe and for stretching the apron, toe embracing wipers carried by said arm and arranged to act upon the apron to lay the margin of the upper inwardly over the sole, and means automatically operative when said arm has substantially completed its movement toward the toe to press said wipers toward the plane of the sole.
145. In a machine of the class described, the combination with a gripper for pulling an upper over a last, of overlaying means movable toward the last for laying the margin of the upper inwardly over the bottom of the last, and mechanism automatically operative independently of the movement of said overlaying means toward the last to trip said gripper for effecting a sudden release of the upper prior to the operation of the overlaying means upon the upper.
146. In a machine of the class described, the combination with a toe gripper for pulling an upper over a last, of toe embracing wipers mounted for advancing and closing movements to lay the margin of the upper about the toe inwardly over the bottom of the last, and mechanism automatically operative independently of the movement of said wipers toward the last to trip the toe gripper to effect a sudden release of the upper prior to the operation of the wipers upon the upper.
147. In a machine of the class described, the combination with a gripper for pulling an upper over a last, of overlaying means movable toward the last for laying the margin of the upper inwardly over the bottom of the last, and means automatically operative independently of the movement of said overlaying means toward the last to clamp the upper against the last and to trip said gripper from the upper prior to the operation of the overlaying means upon the upper.
148. In a machine of the class described, the combination with a toe gripper for pulling an upper over a last, of a front arm mounted for swinging movement toward the toe of the last and carrying means for laying the margin of the upper inwardly over the bottom of the last, and mechanism automatically operative independently of the movement of said front arm toward the last to release the toe gripper from the upper.
149. In a machine of the class described, the combination with a toe gripper for pulling an upper over a last, of toe embracing wipers mounted for advancing and closing movements to lay the margin of the upper about the toe inwardly over the bottom of the last, side clamping devices movable into engagement with the upper at the opposite sides of the last, and mechanism automatically operative in the movement of said side clamping devices toward the last to release the toe gripper from the upper prior to the operation of the wipers on the upper.
150. In a machine of the class described, the combination with a toe gripper for pulling an upper over a last, of a front arm mounted for swinging movement toward the toe of the last and carrying means for laying the margin of the upper inwardly over the bottom of the last, side clamping devices movable laterally of the shoe into engagement with the upper at the sides of the last, and mechanism automatically operative in the movement of said side clamping devices toward the last to release the toe gripper from the upper prior to any substantial movement of the front arm toward the last.
151. In a machine of the class described, the combination with a gripper for pulling an upper over a last, of means for tripping said gripper to release it from the upper, said tripping means comprising an operating member mounted independently of the gripper and flexible connections for operatively connecting said member to the gripper in all positions assumed by the gripper.
152. In a machine of the class described, the combination with a gripper for pulling an upper over a last, of means for tripping said gripper to release it from the upper, said tripping means comprising an operating member and telescopic connections between said member and the gripper for maintaining a continuous operative relation to the gripper in all positions assumed by the gripper.
153. In a machine of the class described, the combination with a gripper for pulling an upper over a last, of means for tripping said gripper to release it from the upper, said tripping means comprising a member pivotally mounted on the gripper, an operating member mounted independently of the gripper, and operating connections between said different members comprising telescoping parts having universal connections respectively with the different members.
154. In a machine of the class described, the combination with a gripper for pulling an upper over a last, of means for tripping said gripper to release it from the upper, said tripping means comprising a jaw tripping latch on the gripper, a member pivotally mounted on the gripper and having a finger for engaging said latch, and mecha-

nism mounted independently of the gripper and connected to said pivotally mounted member for operating it.

155. That improvement in methods of shaping uppers over lasts which consists in engaging an upper on the lateral periphery of a last with a flexible apron and by relative movement between the last and said apron working the upper heightwise of the last, holding the upper against the last by pressure applied to said apron on the lateral periphery of the last, and while thus holding the upper forcing the apron inwardly over the bottom of the last to lay the margin of the upper over the sole.

156. That improvement in methods of shaping uppers over lasts which consists in engaging an upper on the lateral periphery of a last with a flexible apron, applying pressure to said apron on the lateral periphery of the last to hold the apron against the upper and then pulling said apron to work the upper heightwise of the last, and while continuing thus to press the apron against the upper forcing the apron inwardly over the bottom of the last to lay the margin of the upper over the sole.

157. That improvement in methods of shaping uppers over lasts which consists in engaging an upper on the lateral periphery of a last with a flexible apron and while holding said apron at the opposite sides of the plane of the sole, moving the apron and the last relatively to wipe the upper heightwise of the last, and then by engagement with the apron between the points where it is thus held pressing it inwardly over the bottom of the last to lay the margin of the upper over the sole.

158. That improvement in methods of shaping uppers over lasts which consists in engaging an upper on the lateral periphery of a last with a flexible elastic apron and moving the last and said apron relatively to wipe the upper heightwise of the last while stretching the apron to increase its frictional drag on the upper, holding the upper against the last by pressure applied to said apron on the lateral periphery of the last, and while maintaining said apron in stretched condition pressing it inwardly over the bottom of the last to lay the margin of the upper over the sole.

159. That improvement in methods of shaping uppers over lasts which consists in engaging an upper on the lateral periphery of a last with a flexible elastic apron and by relative movement of the last and said apron wiping the upper heightwise of the last while pulling on the apron to stretch it and increase its frictional drag on the upper, and while maintaining the pull on the apron pressing it inwardly between the last and the point where the pull is applied to lay the margin of the upper over the sole.

160. That improvement in methods of shaping uppers over lasts which consists in gripping the margin of an upper and pulling the upper over a last, engaging the upper on the lateral periphery of the last with a flexible apron and then releasing the margin of the upper, wiping the upper heightwise of the last by relative movement between the last and said apron, and pressing said apron inwardly over the bottom of the last to lay the margin of the upper over the sole.

161. That improvement in methods of shaping uppers over lasts which consists in embracing an upper about an end of a last with a flexible apron and wiping the upper heightwise of the last by relative movement between the last and said apron, holding the upper about the end of the last by pressure against said apron, and while thus holding the upper pressing the apron inwardly about the end of the last to lay the margin of the upper over the sole.

162. That improvement in methods of shaping uppers over lasts which consists in embracing an upper about an end of a last with a flexible elastic apron, wiping the upper heightwise of the last by the action of said apron while pulling on the apron to stretch it and increase its frictional drag on the upper, and by engagement with the apron between the last and the point where the pull is applied to the apron pressing the apron inwardly about the end of the last to lay the margin of the upper over the sole.

163. That improvement in methods of shaping uppers over lasts which consists in embracing an upper about an end of a last with a flexible apron, clamping the apron against the upper about the end of the last, pressing the apron inwardly about the end of the last to lay the margin of the upper over the sole, and while thus pressing the apron inwardly pulling on the apron to hold it tight transversely of the plane of the sole.

164. That improvement in methods of shaping uppers over lasts which consists in embracing an upper about an end of a last with a flexible apron, pulling on the apron heightwise of the last, and by engagement with the apron between the bottom of the last and the point where the pull is applied pressing the apron inwardly from the end and side faces of the last to gather the margin of the upper and lay it over the bottom face of the sole.

165. That improvement in methods of shaping uppers over lasts which consists in embracing an upper about an end of a last with a flexible elastic apron and by engagement with said apron at opposite sides of the plane of the sole stretching the apron heightwise of the last, and then by pressure against the apron between the points where it is thus engaged forcing the apron inwardly over the bottom of the last from the

end and side faces of the last to gather the margin of the upper and lay it over the bottom face of the sole.

166. That improvement in methods of shaping uppers over lasts which consists in embracing an upper about an end of a last with a flexible elastic apron, clamping the apron against the upper about the end of the last and pulling on the apron to stretch it heightwise of the last and to draw it inwardly over the edge of the sole, and while thus pulling on the apron pressing it inwardly from the end and side faces of the last between the bottom of the last and the point where the pull is applied to gather the margin of the upper and lay it over the bottom face of the sole.

167. That improvement in methods of shaping uppers over lasts which consists in gripping the margin of the toe end of an upper and pulling the upper over the toe of a last, embracing the toe of the upper with a flexible elastic apron and releasing the margin of the upper, and thereafter pulling the apron rearwardly over the bottom of the last and pressing the apron inwardly from the end and side faces of the toe of the last to gather the margin of the upper and lay it over the bottom face of the sole. 20 25

In testimony whereof I have signed my name to this specification. 30

BERNHARDT JORGENSEN.

CERTIFICATE OF CORRECTION.

Patent No. 1,667,789.

Granted May 1, 1928, to

BERNHARDT JORGENSEN.

It is hereby certified that error appears in the printed specification of the above numbered patent requiring correction as follows: Page 22, line 5, claim 136, for the misspelled word "flexbile" read "flexible"; page 23, line 51, claim 147, for the word "trip" read "release"; and that the said Letters Patent should be read with these corrections therein that the same may conform to the record of the case in the Patent Office.

Signed and sealed this 30th day of April, A. D. 1929.

M. J. Moore,
Acting Commissioner of Patents.

end and side faces of the last to gather the margin of the upper and lay it over the bottom face of the sole.

166. That improvement in methods of shaping uppers over lasts which consists in embracing an upper about an end of a last with a flexible elastic apron, clamping the apron against the upper about the end of the last and pulling on the apron to stretch it heightwise of the last and to draw it inwardly over the edge of the sole, and while thus pulling on the apron pressing it inwardly from the end and side faces of the last between the bottom of the last and the point where the pull is applied to gather the margin of the upper and lay it over the bottom face of the sole.

167. That improvement in methods of shaping uppers over lasts which consists in gripping the margin of the toe end of an upper and pulling the upper over the toe of a last, embracing the toe of the upper with a flexible elastic apron and releasing the margin of the upper, and thereafter pulling the apron rearwardly over the bottom of the last and pressing the apron inwardly from the end and side faces of the toe of the last to gather the margin of the upper and lay it over the bottom face of the sole. 20 25
